United States Patent

Des. 238,982

Patented Mar. 2, 1976

238,982

CORSELETTE

Jack J. Lo Cascio, Bayonne, and Harold Stern, Wyckoff,
N.J., assignors to International Playtex, Inc., New York, N.Y.

Filed Oct. 3, 1974, Ser. No. 511,866

Term of patent 14 years

Int. Cl. D2—01

U.S. Cl. D2—3

FIG. 1

FIG. 2

FIG. 3

FIG. 1 is a perspective front view of a corselette embodying our new design;

FIG. 2 is a side elevational view of FIG. 1, the opposite side being reversely similar; and

FIG. 3 is a rear view thereof.

We claim:

The ornamental design for a corselette, substantially as shown.
